UNITED STATES PATENT OFFICE

LEONARD WOODS, OF ST. LOUIS, MISSOURI

SOCK SUPPORTER

Application filed June 13, 1931. Serial No. 544,205.

This invention relates to certain new and useful improvements in sock supporters, the peculiarities of which will be hereinafter fully described and claimed.

5 The main objects of my invention are first, to provide one or more vertically disposed strips forming stays, props or braces adapted to be fixed to the ankle of the wearer at their lower end and to the top of a sock at their upper end, so as to support a sock in tensioned position on the leg of the wearer; second, to make such a stay with an anklet portion so it may be stamped out of bendable sheet material in one piece and shaped to the leg; third, 10 to make the anklet portion adjustable to fit different sizes of ankle; fourth, to provide such a stay with wear resistant material to prevent chafing the wearer's leg; and fifth, 15 to support both sides of the sock from the ankle.

In the accompanying drawing in which like reference numerals indicate corresponding parts,

Fig. 1 represents my anklet sock supporter 25 applied inside a sock indicated by broken lines;

Fig. 2, a plan view of the anklet portion on the section line 2—2 of Fig. 1;

Fig. 3, a detail of the same as stamped out 30 of sheet metal;

Fig. 4, an enlarged detail face view of the upper end of a stay; and

Fig. 5, a sectional view on the line 5—5 of Fig. 4.

35 My present form of sock supporter provides a vertically disposed strip at one or both sides of the sock, and preferably located in the hollow between the ankle bone and Achilles' tendon, and detachably secured at its upper end to the top of a sock while its lower end is carried by resilient fastening means secured directly to the front and sides of the wearer's leg above the ankle joint but not embracing the rear tendon,

40 which is thus entirely free from any constricting band encircling the leg. By my construction therefore, the reaction of the tensioned sock engaged by the upper end of my stay, is carried directly by a resilient anklet applied to the leg of the wearer near

the ankle joint which serves as a fixed foundation for the bottom end of the stay.

Referring to the drawing, the numeral 6 designates a flat thin strip of sheet metal such as steel or aluminum, the upper end of which is provided with fastening means preferably consisting of a spring clip formed by bending over downward the upper end 7 so that its lower end is closely adjacent to the strip below the top, and will detachably engage the top of an interposed sock. The end of said bent down portion is preferably provided with a ball 8, and the strip opposite the ball has a hole or depression 9 into which the ball will press the interposed sock and hold it by the spring clip. Other fastening means may be provided.

The bottom end of this strip forming a vertically disposed stay, is connected to fastening means embracing the ankle of the wearer's leg preferably at the narrow portion just above the ankle joint indicated at 10 in Fig. 1.

This fastening means preferably consists of a horizontal strip of metal or other suitable material 11 circumferentially embracing the front and sides but not the back of the wearer's ankle like an anklet and is open at the rear so as to avoid any constriction on the heel tendon, and thus forming a rigid support for the bottom of the stay. This anklet portion is adjustable to the size of the ankle by the resiliency of the metal and is prevented from slipping downward both by the enlargement of the ankle joint and by frictional contact of the anklet with the wearer's leg.

To prevent abrasion of the bare metal upon the skin of the wearer's leg, I preferably provide a fabric covering 12 more or less enclosing the stay and anklet portion as indicated. The clip 7 may be covered with chamois 12'.

When one stay is used on the anklet portion, such is preferably located on the inside of the leg as stated above, and when another stay is used as 6', Figs. 1 and 3, the latter is disposed on the outside of the wearer's leg and in the hollow on the outside of the leg adjacent to the Achilles' tendon as indi-

cated in Figs. 1 and 2. The anklet portion does not encircle said tendon.

Fig. 3 represents my sock supporter with two stays and integral anklet portion in flat spread-out position as it would be when stamped or otherwise formed from sheet metal, before the anklet portion is bent to form the loop embracing the front and sides of the wearer's leg. The natural resiliency of the metal causes the anklet to frictionally engage the leg after springing open to apply it thereon.

With my present form of sock supporter, the sock is tensioned in an upward direction only, since the upper end of the stay or stays is engaged to the top of the sock only, and the bottom end of the stay has a support or foundation independent of the sock itself. When two stays are used as above described, the tension of the engaged fastening means at the top of each stay is exerted on each side and around the heel of the sock so that the sock has no tendency to sag or make any fullness at any point, but is held in smooth tensioned position upon the wearer's leg.

While I have described my anklet sock supporter as applied to short hose designated usually as a sock, I may use the same for longer hose by lengthening the stays above described.

By this base afforded by the leg above the ankle, and independent of the sock, my anklet sock supporter is applicable to all socks, old and new, without any addition to the socks themselves.

I claim:

1. A sock supporter comprising a horizontal resilient sheet metal strip and two strips integral therewith and rigidly disposed upward and adapted at their upper ends to engage and support the top of a sock, the horizontal strip being formed to engage the front and sides only of the wearer's ankle after being sprung open to apply it thereon, substantially as described.

2. A sock supporter comprising a resilient, horizontally curved metal strip, open and unconnected at its rear ends and forming a spring anklet adapted to embrace the ankle of the wearer except the heel tendon disposed between said open unconnected rear ends, and rigidly vertically upstanding stay means integrally connected to said anklet and adapted to engage the top of a sock and support it from said anklet, substantially as described.

In testimony whereof I have affixed my signature.

LEONARD WOODS.
